KNITTING MACHINE OF THE OPPOSED NEEDLE CYLINDER TYPE

Frederick Edward Deans, Leicester, England, assignor to The Bentley Engineering Company Limited, Leicester, England

Application March 19, 1951, Serial No. 216,292

Claims priority, application Great Britain March 24, 1950

9 Claims. (Cl. 66—14)

This invention concerns circular knitting machines, primarily those of the type organised to knit tubular fabric by rotation and a pouch by "oscillation" (or reciprocation), and having opposed needle cylinders equipped with double ended latch needles controlled by sliders in the two cylinders and capable of transfer between the two cylinders, a cam box for each cylinder, cams in the boxes for moving the sliders and the needles, said cams in each box including knitting cams operable at a knitting station during rotation and oscillation, and means for producing relative rotation and oscillation between cylinders and the cam boxes. An object of this invention is to effect such improvements in machines of this type as will permit seamless stockings, socks and like articles of footwear to be produced having certain characteristics not heretofore known in such articles of hosiery. A further object of the invention is an attachment for use in a machine of the type specified.

According to the present invention a machine of the type specified is provided with a set of interchangeable yarn feeders at the knitting station, patterning mechanism for effecting their selective interchange at a small group of the needles, auxiliary knitting cams in the two boxes at an auxiliary knitting station spaced circumferentially from the first or main station, an auxiliary yarn feeder at the auxiliary station, feeder control mechanism for introducing and withdrawing the auxiliary feeder as required during rotary knitting, the change being confined to the said group of needles, and for withdrawing it at the commencement of the pouch, and cam control mechanism for rendering the auxiliary knitting cams inoperative when the auxiliary feeder is withdrawn so that the needles continue to knit only at the main station. Preferably, the small group of needles referred to consists of those needles which knit a few wales located centrally at the back of the leg. According to a further feature of the invention the machine has a draw thread feeder at the auxiliary station and the feeder control mechanism is arranged to introduce it during a draw thread course of rotary knitting (the said course being intended to separate successive articles knitted on the machine) and the cam control mechanism is arranged to render the auxiliary knitting cams operative while the draw thread feeder is operative.

If the auxiliary feeder is operative shortly before the commencement of a pouch, primarily the heel pouch, it is undesirable that in this instance its region of withdrawal shall be within the few wales at the back of the leg and it is preferable that its region of withdrawal shall be at the side of the leg so that it is withdrawn after all the needles that are to be employed in the pouch have knitted from it. Therefore according to a further subsidiary feature of the invention the feeder control mechanism is arranged to shift the region of withdrawal of the auxiliary feeder, preparatory to knitting a pouch, to the side of the article.

It will be appreciated that when knitting proceeds at both the knitting stations two courses are produced at each

2

revolution, the fabric being knitted as a two-start spiral whereof one spiral is knitted of the thread fed at one station and the other is knitted of the thread fed at the other station. When knitting proceeds at one station only (e. g. the main station) the fabric is produced as a single-start spiral. Fabrics of the two kinds may alternate and this is an effect that has not hitherto been produced in a seamless sock or the like. Therefore the invention also includes a seamless sock or the like having a leg of which at least part consists of ribbed fabric, and heel and toe pouches of non-ribbed fabric, wherein the leg comprises spaced bands knitted of two distinct threads as a two-start spiral and intervening bands knitted of at least one thread as a one-start spiral, the region of introduction and withdrawal of the various threads of which these bands are knitted being confined to a few wales at the back of the leg.

This invention further provides in or for a circular knitting machine, an attachment comprising a plurality of feeders, a trapper and cutter for each feeder, feeder-control mechanism for introducing and withdrawing each feeder as required, and other control mechanism applicable to the control of needle-operating cams in the machine.

The foregoing and other features of the invention set out in the appended claims are incorporated in the machine and product, which will now be described by way of example with reference to the accompanying drawing in which—

Figure 1 illustrates a seamless sock according to the invention;

Figure 23 is a sectional view taken on the line C, C, in Figure 3 but on a larger scale.

The machine is of the type specified and has the needle

cylinders 1, 2, disposed with their axes vertical, and capable of rotation and oscillation as in the well known machine sold under the registered trademark "Komet."

It is provided at a main knitting station M. K. with yarn changing mechanism 3 according to U. S. Patent No. 1,838,651, with cams such as 4, 5, 6, 7, in the two cam boxes 9, 10, for knitting during rotation, cams 4, 5, in the bottom box 9 for knitting during oscillation in the production of heel and toe pouches, and with pickers 11, 12, 13 for progressively moving the pouch needles from and into activity in known manner. The usual transfer cams 14, 15, 16, and 43 are also provided for transferring the double ended needles 17 between the two cylinders to alter the character of the fabric produced, such for example as between a one and one or other narrow rib in the top of a sock and a six and three or other broad rib in the leg of a sock.

The yarn-changing mechanism 3 incorporates interchangeable yarn feeders 133 and patterning mechanism 134 for effecting their selective interchange but for details of this yarn-changing mechanism reference is to be made to the patent above mentioned. It is to be pointed out, however, that the mechanism 134 is racked by an oscillating pawl carrier 137 (41 in the said U. S. Patent) rocked up and down by a connecting rod 138 and a crank 139 driven from a continuously rotating part 140 of the machine. The crank is so timed in relation to the rotation of the needle cylinders that the selective interchange of the feeders 133 is confined to a small group of needles at or near the back of the leg, which needles knit the group of wales 47 hereinafter mentioned.

Spaced circumferentially from the main knitting station there is an auxiliary knitting station A. K. the spacing may be as convenient, for example 180°. At this auxiliary station A. K. there is an attachment 20 which is removable from the machine as a unit. This attachment 20 comprises two feeders viz. an auxiliary feeder 21 and a draw thread feeder 22, a trapper and cutter 66, 67, for each feeder, feeder control mechanism for introducing and withdrawing each feeder as required, and cam control mechanism for controlling auxiliary knitting cams provided in the two cam boxes 9, 10, to cause needles to knit in each cylinder at the auxiliary station. These auxiliary knitting cams comprise stitch cams 27, 28, in the bottom and top boxes 9, 10, respectively.

At this stage it is convenient to describe the movements of the needles 17 and their sliders 29, 30, in the production of socks such as that illustrated in Figure 1, said socks being knitted in continuous fashion separated by a draw thread (as in British Patent No. 400,623) having a welt 31 followed by a one and one top 32, a six and three (or other rib arrangement) leg 33 composed of bands 34 of single feed fabric with intervening bands 35 of double feed fabric, a heel pouch 36 knitted by reciprocation, a foot 37 also composed of said alternating bands of single feed and double feed fabric, and a toe pouch 38.

After having finished the toe of the previous sock, all the needles 17 are in the bottom cylinder 1 and the machine is knitting plain fabric. After a few waste courses of the plain fabric, each alternate needle is transferred up into the top cylinder 2 to make one and one ribbed fabric; the tracks followed by the butts 39, 40, of the associated sliders 29, 30, are shown as *a* and *b* in Figure 7.

To knit the draw thread, bolt cam 41 is brought into action (i. e. moved in towards the cylinder) to deflect the butts 39 of the bottom sliders 29 into track *c* where they draw a loop of the new thread from the draw thread feeder 22 which has been introduced by the attachment 20 at the second feed station. The rib needles in the top cylinder 2 hold their loops (received at the main feed station M. K.) and, pursuing track *b*, do not take this new thread. In a specific example, the draw thread is introduced at the side of the sock or the like (i. e. at the first long butt instep needle) and is withdrawn at

the centre of the back of the leg (i. e. in the middle of the short butt heel needles) so that it is knitted for about 1 1/4 courses. At the introduction of the draw thread the two-position crank hereinafter described is in its late position, and at the withdrawal the crank is in its early position. When the draw thread feeder 22 is withdrawn, the auxiliary knitting cams are rendered inoperative.

The welt or reverse welt 31, as required, is made in the usual way, the bolt cams 42 and 7 in the top cam box 10 being withdrawn in making the welt, and the bolt cams 44 and 45 in the bottom box 9 being withdrawn in making a reverse welt. After the welt 31, a one and one top 32 is made by bringing the necessary bolt cams back into action to deflect the butts of the sliders back to tracks *a* or *b* as required. This rib top is conveniently knitted (as a single start spiral) solely from yarn fed at the main station M. K. or as a two start spiral from yarns fed at both stations (as hereinafter described in relation to the leg); for example for the purpose of speeding-up production or achieving a two-coloured effect.

Next, the usual double transfer is made to select needles to make the broad rib leg portion 33, and it is in this portion that the bands 35 of double feed fabric are to appear.

Now when making the single feed fabric, the butts 39, 40, of the sliders 29, 30, follow tracks *a* and *b*, but when it is desired to bring the second or auxiliary feeder 21 into action, the bolt cams 41 and 44 in the bottom box 9 and bolt cams 42 and 46 in the top box 10 are moved in towards the cylinders 1, 2, to deflect the butts of the sliders into tracks *c* and *d* respectively. Thus, the needles in both cylinders are caused to clear their old loops (formed at the main stitch cams 5 and 6) and receive the second yarn and draw loops of it at stitch cams 27 and 28, clearing these last formed loops at bolt cams 44 and 42.

It can be seen from the above that alternating bands of single feed fabric 34 and double feed fabric 35 may be made simply by withdrawing and introducing of the aforementioned bolt cams 41, 44, 42, 46 and the auxiliary feeder 21 all being controlled by the attachment 20 at the second feed station, A. K.

The introduction and removal of the auxiliary feeder 21 takes place at the back of the leg during the manufacture of the leg 32 of the sock (being confined to a small group of wales 47 as shown) but if it is desired that the auxiliary feeder should be in operation right up to the commencement of the heel pouch 36 (or the toe pouch 38) when it is preferable that it should be withdrawn either after all the pouch needles have knitted it, or before any of them knit it. This requires a modification of the normal slider butt set-up, as it is necessary to insert a group of medium length knitting butts 39*m*, among the short butts 39*s* of the heel half in the bottom cylinder and a group of long butts 40*l* among the medium butts of the heel half in the top cylinder, as shown in Figures 8 and 9, to enable the bolt cams to be inserted or removed.

After knitting the heel pouch 36, the auxiliary feeder 21 may again be brought into action. To ensure that the auxiliary feeder supplies yarn to the needles that knit the first instep course after the heel, bolt cam 46 in the top box 10 and bolt cam 41 in the bottom box 9 are introduced to divert the butts 40, 39, of the sliders into tracks *d* and *c* respectively. The introduction of these cams is timed in the following manner:

At the moment when the cylinders 1, 2, are stationary, having made the last reciprocation in making the heel, the instep half sliders having the long butts 39*l*, 40*l* (which are in the high nonknitting track) extend approximately from about T to point U on the cam box layout Figure 7. When rotary knitting commences, these long butted sliders continue in the high track until they reach the bolt cam 48 in the top box 10 and cam 49 in the bottom box 9 (these cams having just been introduced

from whence they are diverted to their normal knitting tracks. If reference is made to Figures 8 and 9 it will be seen that the long butts 40^l of the instep sliders in the top cylinder are followed by medium butts 40^m (Figure 8) and the long butts 39^l of the instep sliders in the bottom cylinder are followed by a small group of medium butts 39^m followed by short butts 30^s (Figure 9).

Now at the commencement of rotary knitting after the heel the knitting butts 39 of all the bottom cylinder sliders 29 of the heel half are in the normal knitting track *a* between points T and U, Figure 7 except the first two sliders of group 39^m following the long butts 39^l Figure 9, because these two sliders have been left up in the non-knitting track during the preceding picking operations. In this first revolution the butts of these two sliders are deflected down feed cam 4 and stitch cam 5 and are then raised by cam 45, being thereafter deflected to stitch cam 27 by bolt cam 41 (which has just been inserted beneath the preceding long butts 39^l). Thus the first needle to knit, at both feeding positions, in the production of double feed fabric after the heel is the needle controlled by the third slider of group 39^m. During the first revolution, cam 49 is introduced to lower the long butts 39^l of the instep sliders to knitting track *a*.

In the top cylinder the sliders 30 of the heel half (disposed between the points T and U at the start of rotary knitting after the heel) continue in the non-knitting track, the butts of these sliders passing in front of inoperative bolt cam 48. Before the first long butt of group 40^l in the heel half reaches it this cam 48 is moved in, firstly part-way (just clear of medium butts 40^m) and then fully, so that it raises butts 40^l and all following butts to the normal knitting track. In this track, the first needle to knit at stitch cam 6 is the first instep needle (i. e. the first needle, whereof the slider 30 has a long butt 40^l) it being understood that before starting on the heel sliders in the top cylinder transfer their needles to heel sliders in the bottom cylinder.

After knitting at the main cam 6, the instep needles also knit at the second stitch cam 28, bolt cam 46 having been introduced at about the same time as bolt cam 41 of the bottom cam box. Thus, double fabric is knitted immediately after knitting the heel the start being confined to the group of wales 47.

Further bands of single feed fabric alternating with bands of double feed fabric may be knitted throughout the foot, the article finally being finished by knitting the toe pouch.

Having now described a typical article and its method of manufacture, the attachment of unit for operating the various bolts, feeders and trappers will be described in detail.

Preferably, the feeder control mechanism provided in the attachment 20 is within the scope of the aforesaid U. S. Patent No. 1,838,651. It, and the cam control mechanism, comprise three patterning units 50^a, 50^b, 50^c rotatable individually about a common axis 51.

These units are shown in Figures 10 and 11, 12 and 13, and 14 and 15 respectively. Each of them comprises a ratchet wheel 52^a, 52^b or 52^c having alternate long and short teeth, and for each of these wheels there is a drag pawl or clawer 53^a, 53^b or 53^c, in Figures 4 and 6 pivoted in a pawl carrier 54. The pawls are maintained in contact with their associated ratchet wheels by means of a light tension spring (not shown). The pawl carrier 54 is mounted so as to rock about the shaft 51 which is fixed in the main bracket 55. From this it will be seen that, as the pawl carrier 54 is rocked about the shaft 51, each drag pawl will engage a tooth of the ratchet wheel contained in its associated patterning unit and on the downward oscillation of the carrier, the pawl will rock its unit about the fixed shaft 51.

The left hand unit 50^a is shown in detail in Figures 10

75

and 11. This unit forms part of the cam control mechanism and comprises besides the ratchet wheel 52^a an adjustable cam carrier 56^a and two cam discs 57^a and 58^a. The carrier 56^a is secured in fixed relationship to the ratchet wheel 52^a and the cam discs 58^a by screws 59, but the cam disc 57^a being mounted on a shoulder of the carrier 56^a is free to move within the limits decided by the adjustment of the two screws 60, 60' acting on the fixed peg 61, thus providing means for "timing" cam 57^a with respect to the ratchet wheel 52^a and the cam 58^a. This unit operates the auxiliary knitting cams in the following manner:

Cam 57^a operates lever 62 (Figs. 4 and 6) which is connected by means of the link 63 to the operating lever 121 attached to bolt cam 7 (see Figures 2, 3, 4, 6 and 23). In similar manner cam 58^a operates lever 64 which is connected by means of the link 65 to the operating lever 122 attached to bolt cam 41, Figure 7.

The middle unit 50^b is shown in detail in Figures 12 and 13. This unit controls the draw thread feeder 22, Figures 4 and 6 and its trapper 66 and comprises ratchet wheel 52^b and two cam discs 57^b, 58^b. Cam 57^b operates lever 68, Figures 4 and 6, which, through the adjustable contact of the screw 69 of the swivel lever 70 causes the feeder 22 which is mounted in lever 70 to move in an arc between feeding position and trapping position. The screw 69 of lever 70 is urged into contact with lever 68 by the tension spring 71, one end of which is attached to the post 72 by means of the hook 73. This post 72 carries two adjustable stop screws 74, 75, which provide stops for the tails 70', 76' of the swivel levers 70 and 76 when the feeders are swung to the feed position. For details of feeder post assembly, see Figures 19-21.

Cam 58^b of the same middle unit 50^b operates lever 77 through an adjustable cam follower 78, Figure 6. Lever 77 has a tappet 79 which engages rod 80. If reference is made to Figures 16-18 it will be seen that rod 80 is screwed into the block 81 which is slidably contained in the tube 82. Clamped to the tube is the bracket 83 which carries the two trappers 66, 67. When the rod 80 is lifted, the block 81 acts on the round end 91^a of the trapper lever 91 and opens trapper 66.

The right hand unit 50^c functions in a similar manner to the middle unit 50^b but operates the auxiliary feeder and trapper.

This unit is shown in detail in Figures 14 and 15 and comprises ratchet wheel 52^c and two cam discs 57^c and 58^c. Cam 57^c operates lever 84, Figures 4 and 6 which is mounted with lever 68 on shaft 85 and through the adjustable contact of the screw 86 of the swivel lever 76, causes the feeder 21, which is fixed in lever 76, to move in an arc between feeding and trapping positions.

The screw 86 of the swivel lever 76 is urged into contact with the lever 84 by the torsion spring 87. Cam 58^c of right hand unit 50^c operates lever 88 (which is identical with lever 77 and is concealed by it in Figure 6) and lever 88 operates rod 89 (through an adjusting screw such as 79, Figure 6).

Referring to Figures 16-18, rod 89 is screwed into the block 90 slidably contained in the tube 82. When rod 89 is lifted, block 90 acts on the round end 92^a of the trapper lever 92 and opens trapper 67.

The working arrangement of the attachment 20 is such, that when a feeder 21 or 22 is in feeding position its control unit 50^b or 50^c presents a long tooth of the ratchet wheel 52^b or 52^c for engagement by the associated pawl 53^b, 53^c and when it is out of feeding position, the unit presents a short tooth towards this pawl. Likewise, the arrangement of the cam control unit 50^a is such, that when the auxiliary knitting cams 41 and 45 are operative, a long tooth of ratchet wheel 52^a is presented to the pawl 53^a and when they are inoperative, a short tooth is presented. The reason for this will become clear in the following description:

The pawls 53^a, 53^b, 53^c, Figures 4 and 6, are con-

trolled by a selector bar 93 which is slidable parallel to the axis of the units and corresponds to the bar 53 of the aforesaid Patent No. 1,838,651, being arranged to co-operate with the tails of the pawls, and being so slotted as to provide for three alternative positions for each pawl, viz:

1. A completely bluffed position in which the tail of the pawl rides on the highest point (or top) 94 of the selector bar 93, Figure 4 and therefore does not rack the ratchet wheel.

2. A position in which the tail of the pawl rides on the step (such as 95) of the selector bar and thus engages a long tooth.

3. And a position where the tail rides in the bottom or lowest point (such as 98) allowing the pawl to engage either a long or a short tooth.

The selector bar 93 is movable endwise to make its selections, by means of a sector cam 99, Figures 4 and 6 which is capable of rotary adjustment about the axis of the units and engages between two stop screws 160 and 101 on the selector bar 93 so that, as the sector is rotated in either direction, the selector bar is moved positively. Its flanks are stepped to give four positions for the selector bar as follows:

Position 1 (the extreme left hand position) in which all three pawls are bluffed and therefore oscillate idly.

Position 2, in which all three pawls are capable of engaging only the long teeth, so that if either feeder 21, 22, is or the auxiliary knitting cams 41, 46 are in operation, the same is/are brought out of operation at the first stroke of the pawls.

Position 3, in which the pawls of units 50a and 50c are permitted to engage short teeth (or long teeth if such are presented) so these units are racked to withdraw (or introduce) the auxiliary feeder 21 and the knitting cams 41, 46.

Position 4 (the extreme right hand position) in which the pawls of units 50a and 50c are permitted to engage short teeth (and necessarily long teeth if such are presented). Thus, these units are racked to withdraw (or introduce) the draw thread feeder 22 and the knitting cams 41, 46.

The selector bar 93 is also cut with a pair of spaced notches 102, 103, Figure 4 into one or other of which a finger 104 on the pawl carrier 54 may enter on the up stroke of the carrier, in certain positions of the bar. The "land" 105 between these two notches is arranged by engagement with this finger 104 to delay movement of the bar 93 from position 1 or from position 3 until the pawls have moved far enough down their racking stroke for their tails to move off the bar.

The sector 99 is rocked in one direction, against the action of the spring 106, Figure 22, by means of a spring loaded connection 107 operable from the main control drum 123 of the machine. This connection 107 yields temporarily if movement of the selector bar 93 is temporarily prevented by the finger 104. On the control drum 123, there is a cam 124 which, in the event of the machine being turned back by hand to a start position, operates (through the cam sector 99 or otherwise) to shift the selector bar 93 to position 2, so that if either feed is, and the auxiliary knitting cams are, operative, it and they are rendered inoperative. The selector bar 93 may be controlled by studs or cams on the chain of the machine, in addition to cams on the control drum. Among the cams on the main control drum 123 for shifting the selector bar, there is a cam 125 attached to the drum at such a position and of such a height, that the bar is moved to position 2 immediately before the heel, and a like cam 126 arranged to operate before the toe.

These cams 125, 126, ensure that the auxiliary knitting cams are not in operation when the machine starts to reciprocate and so prevent damage and give freedom for the setting out of chain studs or cams (to produce changes between single and double feed, as desired) without the

70
75

necessity for making sure that the chain set-out includes provision for a single feed at the beginning of the heel and of the toe.

The normal timing of the racking of the patterning units is such that introduction and withdrawal of the auxiliary feeder 21 could take place at the side of the sock or the like. Therefore, if it is required to bring the change to the back of the leg, such as for knitting bands of double feed fabric during the leg, or for instance the withdrawal of the draw thread feeder (as described earlier) it is necessary to delay the racking.

Now the racking is effected by means of the crank 108 Figures 4 and 6 mounted on shaft 109 carried in bearings in the main bracket 55. This crank is connected to the pawl carrier 54 by connecting rod 110, and mechanism is provided whereby the crank has two positions relative to the crank shaft. This mechanism will now be described with reference to Figure 5. The crank 108 is rotatably mounted on the crank shaft 109 and is drawn by the spring 111 (anchored to crank 108 by screw 112) round the shaft until the stop pin 113 in the crank comes into contact with the abutment 114 which is secured to the shaft. A latch 115 is provided on the shaft for locking the pin in this position. This is the normal (early) position of the crank and would result in the pawl carrier 54 Figures 4 and 6 being rocked at such a time as will cause the introduction and withdrawal of the auxiliary feeder to occur at the side of the leg. In order to delay the introduction and withdrawal of the auxiliary feeder, the latch 115 is tripped so that the crank lags behind the crank shaft.

The tripping is effected by means of the lever 116, Figure 6. When the control rod 117 is operated by a cam on the main control drum, it causes the curved portion 118 of the lever 116 to press on the projection 119, Figure 5 of the latch 115 to swing the latch inwards to release the stop pin 113 and it is now that the weight of the pawl carrier 54 Figures 4 and 6 acting through the link 110 on to the crank 108, delays the crank whilst the stop screw 120 (rotating with the shaft) catches up with the stop pin 113; this stretches the tension spring 111 in preparation for returning the crank to its normal position.

As mentioned previously, if the auxiliary feeder 21 is in operation up to the commencement of the heel pouch 36 (or the toe pouch 38) it is desirable that it should be withdrawn either after all the pouch needles have knitted it, or before any of them knit at it, and this necessitates the crank 108 being latched in its normal position.

The crank shaft 109 is driven by a part 127 (Figure 2) of the knitting machine which rotates and oscillates with the needle cylinders 1, 2. This results in the pawl carrier 54 being oscillated during the production of the pouches, but at this stage all the pawls are bluffed. Thus, the timing of various mechanisms which control auxiliary yarn changes does not become deranged by the change-over between rotation and oscillation.

The two feeders 21, 22 of the attachment 20 are arranged to swing about the vertical axis of the shaft 132, into and out of knitting position. They each terminate in a feeding eye 21' or 22', and the eye of the operative feeder (whichever it may be) must be located at a fixed height relative to the cylinder 1, 2. Therefore, one of the feeders (i. e. feeder 22 Figures 4 and 5) is mounted so that when out of feeding position, its eye 22' is spaced vertically from the eye 21' of the other feeder 21, but as it swings into feeding position, its eye moves into the feeding position that would be occupied by the eye of feeder 21.

Conveniently, the lower feeder (or draw thread feeder 22 as described herein) is hinged at an intermediate point 128 in its length for up and down movements of its free end (whereat the eye is formed) about a horizontal axis, and its hinged part carries a peg 129, Figures 4, 19, 20, and 21, travelling along a slot 130 in a stationary cam

plate 131 which slot is so shaped that the eye 22' rises (against the action of spring 135) as it swings to feeding position and, as it swings out of feeding position, descends to take its place below the inoperative position occupied by the eye 21' of the top feeder 21.

What I claim is:

1. A circular knitting machine of the axially opposed double cylinder type organized to produce seamless stockings, socks, and like articles of footwear having a tubular knitted part including a leg, and a pouch, said machine having opposed needle cylinders, needles in the cylinders, a main knitting station, a cam box for each cylinder, main knitting cams in each cam box at the main knitting station, means for effecting relative rotation between the cylinders and the cams and consequently between the needles and the main knitting station for producing the tubular part, and means for changing from said relative rotation to relative reciprocation for producing the pouch, and further having a set of interchangeable yarn feeders at said main knitting station, patterning mechanism for effecting their selective interchange coincident with the presentation of a small group of the needles at the main knitting station, an auxiliary knitting station spaced circumferentially from the main station, auxiliary knitting cams in each cam box at said auxiliary station, an auxiliary yarn feeder at the auxiliary station, feeder control mechanism for introducing and withdrawing the auxiliary feeder during the production of required courses of the tubular part and at a stage in the production of each of these courses coincident with the presentation of said group of needles at the auxiliary station, and for withdrawing it at a stage in the production of the article coincident with the commencement of said relative reciprocation and commencement of production of the pouch, cam control mechanism for rendering the auxiliary knitting cams inoperative when the auxiliary feeder is withdrawn so that the needles continue to knit only at the main station, and a movable control member common to said feeder control and cam control mechanisms for controlling actuation of said mechanisms.

2. A machine as claimed in claim 1 having a group of needles which knit a few wales located centrally at the back of the leg and constitute the aforesaid group of needles.

3. A machine as claimed in claim 1 having another feeder, at the auxiliary station, movable into and out of operative position, and cam control mechanism arranged to render the auxiliary knitting cams operative while said other feeder is operative.

4. A machine as claimed in claim 3 wherein said other feeder is a draw thread feeder.

5. A machine as claimed in claim 1 having needle controlling butts operable by the knitting cams, and wherein the butts of a localized group have a length contrasting with that of adjacent butts so as to permit the insertion of cams by the cam control mechanism.

6. A machine as claimed in claim 1 having the feeder

control mechanism arranged for altering the stage during production of a course whereat the auxiliary feeder is withdrawn, when commencing to produce the pouch, to be at a stage in the production of the course coincident with needles on which a side of the article is knitted being presented at the auxiliary station.

7. A machine as claimed in claim 6 having racking mechanism for the feeder control mechanism and the cam control mechanism, and means for altering the timing of the racking mechanism.

8. A circular knitting machine of the axially opposed double cylinder type, having opposed needle cylinders, needles in the cylinders, a main knitting station, a set of interchangeable yarn feeders operable at the main knitting station, patterning mechanism for effecting their selective interchange, racking mechanism for racking the patterning mechanism to change its selection, an auxiliary knitting station spaced circumferentially from the main station, a cam box for each cylinder, main knitting cams in each cam box at said main station, auxiliary knitting cams in each cam box at said auxiliary station, an auxiliary feeder movable into and out of feeding position at the auxiliary station, feeder control mechanism for moving the auxiliary feeder into and out of feeding position as required, cam control mechanism for rendering the auxiliary knitting cams operative only when the auxiliary feeder is in operation, common control means for said feeder control and cam control mechanisms, said feeder control and cam control mechanisms including patterning mechanism, and racking mechanism for racking the patterning mechanisms in timed relation for the yarn changes at both stations to be effected at required stages during the production of the article coincident with the presentation of one and the same group of said needles at the respective stations.

9. A machine as claimed in claim 1 having means for ensuring that the auxiliary knitting cams are inoperative at a stage in the production of the article coincident with the commencement of said relative reciprocation.
